(57) **CLAIM**

The ornamental design for an aircraft exterior, as shown and described.

DESCRIPTION

FIG. 1 is a front perspective of an aircraft exterior showing my new design according to a first embodiment;

FIG. 2 is a top view thereof;

FIG. 3 is a left-side view thereof, the right-side view being a mirror thereof;

FIG. 4 is a bottom view thereof;

FIG. 5 is a front view thereof;

FIG. 6 is a rear view thereof;

FIG. 7 is a front perspective of an aircraft exterior showing my new design according to a second embodiment;

FIG. 8 is a top view thereof;

FIG. 9 is a left-side view thereof, the right-side view being a mirror thereof;

FIG. 10 is a bottom view thereof;

FIG. 11 is a front view thereof;

FIG. 12 is a rear view thereof;

FIG. 13 is a front perspective of an aircraft exterior showing my new design according to a third embodiment;

FIG. 14 is a top view thereof;

FIG. 15 is a left-side view thereof, the right-side view being a mirror thereof;

FIG. 16 is a bottom view thereof;

FIG. 17 is a front view thereof; and,

FIG. 18 is a rear view thereof.

The broken lines in the drawings depict portions of the aircraft exterior that form no part of the claimed design.

1 Claim, 15 Drawing Sheets
